(57) **CLAIM**

The ornamental design for a manual sorting device, as shown and described.

DESCRIPTION

FIG. 1 an upper right front perspective view of a manual sorting device showing my new design;

FIG. 2 is a bottom view showing my new design;

FIG. 3 is a front elevational view showing my new design, the rear elevational view being a mirror image thereof;

FIG. 4 is a top plan view showing my design; and,

FIG. 5 is a right side elevational view showing my new design, the left side elevational view being a mirror image thereof.

1 Claim, 2 Drawing Sheets
